UNITED STATES PATENT OFFICE.

LOUIS V. LUCIA, OF HARTFORD, CONNECTICUT, ASSIGNOR TO THE FULLER BRUSH COMPANY, OF HARTFORD, CONNECTICUT, A CORPORATION OF CONNECTICUT.

COMB-CLEANING BRUSH.

Application filed January 3, 1922. Serial No. 526,690.

To all whom it may concern:

Be it known that I, LOUIS V. LUCIA, a citizen of the United States, and a resident of Hartford, in the county of Hartford and State of Connecticut, have invented a new and Improved Comb-Cleaning Brush, of which the following is a specification.

My invention relates to brushes particularly applicable for the clearing of combs, and an object of my invention, among others, is to provide a brush with the use of which a comb employed for toilet and other uses may be cleaned in a particularly rapid and efficient manner.

15 One form of my improved brush, and in the construction and use of which the objects herein set out, as well as others, may be attained, is illustrated in the accompanying drawings, in which—

20 Figure 1 is a side view of my improved brush.

Figure 2 is an end view of the same.

Figure 3 is a view looking toward the edge of the handle of my improved brush.

25 Figure 4 is a fragmentary view illustrating the manner of mounting the brush.

Figure 5 is a view in section on plane denoted by the dotted line 5—5 of Figure 4.

Figure 6 is a view in section simply 30 through the brush and through a comb on a plane cutting across the teeth of the latter, and showing the operation of the brush in removing the dirt from such teeth (scale enlarged).

35 Figure 7 is a perspective view of a comb and of my improved brush illustrating the manner of use of said brush.

Figure 8 is a fragmentary view of a comb and of my improved brush illustrating one 40 manner of use of the brush.

The teeth of a comb used for combing purposes readily collect dirt and other impurities from the skin and scalp and this is particularly true of combs used for combing human hair, as the oil and other moisture from the scalp causes the dirt to cake and become quite hard on the sides of the comb teeth, and to a degree to require considerable effort and force to remove it. By 45 the use of my improved cleaning brush in the manner herein set out one is enabled to thoroughly clean a comb in a particularly rapid and efficient manner, such cleaning brush embodying my invention including a handle 10 having a head 11 that

is formed with two brush supporting arms 12—13 extending preferably in substantially parallel relation from one edge of the head and being provided with means for rotatably supporting a brush 14. The handle and head are formed from a single piece of material, preferably celluloid, that is comparatively thin, the handle, head and arms all being of the same thickness, in the preferred construction each of said supporting arms having a recess 15 formed in its end and on that edge facing the edge of the other arm.

The brush 14 may be of any desired construction but in any event having trunnions 16 projecting from opposite ends thereof, which trunnions are located in the recesses 15, and which recesses are closed at their outer ends, and at the ends of the brush supporting arms to retain the trunnions of 70 the brush in place. In the preferred manner of closing the recesses strips 17 are folded over the ends of the arms and across the recesses and are extended a short distance along the sides of the arms, to which they are secured. In a particularly satisfactory construction of brush the handle 10, head 11, and arms 12 and 13, as hereinbefore mentioned, are formed of celluloid, and the strips 17 are likewise composed of celluloid, said strips being secured to the arms by adhesion. The brush or brush head is preferably of the so called "twisted-wire" type in which the bristles 18 are secured in a twisted wire core 19 and extend radially 80 therefrom to form said head, the ends of said core being extended beyond the brush to form the trunnions 16.

In the use of the brush to clean the teeth of a comb, the latter is held in one hand and the brush is held in the other hand, with the head and handle of the brush extending in the same general direction as the teeth of the comb, and as illustrated in Figure 7 of the drawing, and the brush being 90 then moved rapidly to-and-fro along the comb towards its ends the accumulated dirt on the inner sides of the teeth will be found to be quickly removed, the manner in which the dirt is displaced and removed being 95 graphically illustrated in Figure 6 of the drawing, in which operation, as the brush is moved to-and-fro along the teeth, such brush is rotated in the arms 12 and 13 and 100 the ends of the brush bristles first en- 105 110

countering the sides of the comb teeth at the points *a* push and crowd the dirt downwardly, it being observed that this is a "rooting" action whereby the dirt is plowed and raised from the surface of the teeth as distinguished from a brushing action. The bristles, as the brush is moved in one direction, enter the spaces between the successive teeth of the brush, and as such bristles are forced downwardly the dirt is plowed and pried away from the surface of the teeth and is crowded down through the spaces between the teeth and as the bristles pass upwardly out of the spaces between the comb teeth, as they are caused to do by the rotation of the brush, a sweeping action takes place on the opposite sides of the teeth from those from which the dirt has just been removed. As the brush is moved in the opposite direction it is rotated in a reverse direction to that just above described and the action of the bristles just set out is repeated on the opposite sides of the comb teeth from those from which the dirt has just been removed, the upward sweeping action of the bristles, above mentioned, serving to remove any loose dirt that may by chance remain in the spaces between the comb teeth. In this movement of the brush back and forth along the comb the outer end of the arm 13 may rest upon the flat surface 20 of the comb and thereby form a guide or rest for the brush in its movements.

When it is desired to clean the edge of the comb base at the root of the teeth the brush may be inclined, as indicated in Figure 8 of the drawings, and this position of the brush will effectually clean the entire space between the comb teeth.

The handle 10 and head 11 are preferably so constructed as to be more or less resilient or flexible so that the arms or branches 12-13 may be relatively sprung or abnormally positioned to permit insertion and removal of the brushes, the head being flexed

sufficiently for this purpose. The bristles 18 will be of such length as to pass entirely through the teeth of a comb and for a considerable distance beyond the opposite edges of said teeth, so that the accumulation on 50 the sides of such teeth will be effectually plowed and pried off.

In accordance with the provisions of the patent statutes I have described the principles of operation of my invention, together 55 with the device which I now consider to represent the best embodiment thereof; but I desire to have it understood that the device shown is only illustrative and that the invention may be carried out by other means 60 and applied to uses other than those above set out.

I claim—

1. A comb cleaning brush comprising a handle and a head supported thereby, 65 branches extending from said head and having recesses in their outer ends, bands extending around the ends of the branches to close the recesses at said ends, said bands being secured to the side of the branches, 70 and a brush comprising radially arranged bristles, said brush being mounted to rotate freely in said head to mesh said bristles with the teeth of a comb as the brush is passed to-and-fro on said teeth. 75

2. A comb cleaning brush comprising a handle and a head formed of a single piece of comparatively thin material, arms extending from said head and having recesses in their outer ends, bands composed of the 80 same material as the head passed around the ends of said arms to close said recesses at said ends, said bands being secured by adhesion to the sides of the arms, and a brush comprising radially arranged bristles, said 85 brush being mounted to rotate freely in said head to mesh said bristles with the teeth of a comb as the brush is passed to-and-fro on said teeth.

LOUIS V. LUCIA.
